MOLDED CUSHION

Perley D. Hammond, Danbury, Conn.

Application January 7, 1941, Serial No. 373,505

5 Claims. (Cl. 155—166)

This invention relates to cushions, and more particularly to a resilient cushion for use with kneeling benches, seats, steps or the like.

An object of this invention is to provide a resilient cushion which is formed of an inner cushion body, such as sponge rubber, and an outer resilient covering which is adapted to be vulcanized to the inner body.

Another object of this invention is to provide a cushion of this type which is so constructed that it may be readily adapted to long kneeling benches or seats or individual benches or seats.

A further object of this invention is to provide a cushion which when in applied position may be readily cleaned with a liquid, and which is so constructed that the cleaning liquid will not seep into the cushion and thus damage the cushion.

A still further object of this invention is to provide a cushion of this type and an improved mounting means therefor so that the cushion and the mounting means may be adhesively secured to the desired part.

To the foregoing objects and to others which may hereinafter appear, the invention consists of the novel construction, combination and arrangement of parts as will be more specifically referred to and illustrated in the accompanying drawing wherein are shown embodiments of the invention, but it is to be understood that changes, variations and modifications may be resorted to which fall within the scope of the invention as claimed.

In the drawing:

Figure 1 is a detail top plan of a cushion constructed according to an embodiment of this invention.

Figure 2 is a sectional view taken on the line 2—2 of Figure 1.

Figure 3 is a sectional view taken on the line 3—3 of Figure 1.

Figure 4 is a fragmentary sectional view taken on the line 4—4 of Figure 1.

Figure 5 is a bottom plan of the cushion.

Figure 6 is a fragmentary sectional view of a modified form of holding member for the edge of the cushion.

Figure 7 is a fragmentary top plan of a modified form of cushion.

Figure 8 is a fragmentary bottom plan of a further coupling or joint between adjacent cushions.

Figure 9 is a fragmentary bottom plan of another form of coupling or joint.

Referring to the drawing, the numeral 10 designates generally a resilient substantially thin

sheet-like cover member of material such as rubber or the like, which is formed with an upwardly offset pocket forming member 11. The upwardly offset part 11 forms a pocket 12 opening on the lower side of the member 10 and the opposite ends of the pocket 12 are of substantially semi-circular configuration as at 13. The longitudinal edges of the upwardly offset part 11 are rounded as at 14 and the rounded edge portion is continued about the semi-circular end portions 13. The upwardly offset part 11 forms a pair of longitudinal flanges 15 and 16, the flange 15 being a forward flange and the flange 16 being a rear flange. The member 10 is also formed with end flanges 17 and when in applied position, the sheet 10 is adapted to be adhesively secured to a flat supporting member 18 preferably of wood and which may be a kneeling bench, a step, seat or other support.

The pocket 12 is adapted to have positioned therein a resilient cushion body 19 which is preferably formed of sponge rubber, the body 19 being initially formed of a configuration coincident with the configuration of the pocket 12 and the body 19 is then adapted to be adhesively secured as by vulcanizing or the like within the pocket 12. The lower face 20 of the cushion body 19 is adapted to be disposed substantially flush with the lower faces of the flanges about the marginal edges of the pocket 12 and the body 19 is adapted to be adhesively secured to the upper surface of the supporting member 18.

In order to provide a means whereby the cushion structure including the member 10 and the cushion body 19 may be firmly secured to the supporting member 18 so that moisture or the like will not loosen the adhesive used to secure the cushion to the supporting member 18, I have provided a pair of oppositely disposed end securing or holding members of like form generally indicated at 21, a front pair of spaced endwise aligned channel-shaped front securing or holding members 26 of like form and a pair of spaced endwise aligned channel-shaped rear securing or holding members 26a of like form. The members 26 are oppositely disposed with respect to the members 26a. The members 26, 26a are of like form. Each member 21 is of U-shaped contour in transverse cross section and includes a bight 22, an upper leg 23, a lower leg 24, a front wall 25 and a rear wall 25a. The walls 25, 25a close the front and rear of the member 21 and coact with the bight 22, legs 23, 24 to form an inwardly opening element of pocket-like form. The bights 22 of the members 21 are adhesively secured to

the ends of the supporting member 18. The upper legs 23 of the members 21 are adhesively secured to the upper faces of the flanges 15. The lower legs 24 of the members 21 are adhesively secured to the underside of the supporting members 18. The walls 25, 25a engage against end portions of the front and rear edges of the supporting member 18. Each member 26, 26a consists of a bight 27, an upper leg 28 and a lower leg 29. The bights 27 of the members 26 are secured to the forward edge of the supporting member 18. The legs 28 of the members 26 are adhesively secured to the upper face of the front flange 15. The legs 29 of the members 26 are adhesively secured to the underside of the supporting member 18. The bights 27 of the members 26a are secured to the rear edge of the supporting member 18. The legs 28 of the members 26a are adhesively secured to the upper face of the rear flange 16. The legs 29 of the members 26a are adhesively secured to the underside of the supporting member 18. The outer ends of the front members 26 abut the legs 23, 24 and wall 25 of the end members 21. The outer ends of the rear members 26a abut the legs 23, 24 and 25a of the member 21.

The cover member 10 is formed of a pair of inner edgewise abutting sections 10a, 10b. The cushion 19 is formed of a pair of inner edgewise abutting sections 19a, 19b. The cushion section 19a is formed with a right angularly disposed inner edge 30 which is positioned inwardly from the adjacent inner right angular edge 31 of the cushion covering so as to thereby form a mortise or recess 32. The other cushion section 19b is formed with an extension 33 which extends forwardly beyond the adjacent right angular edge 34 of the cushion covering and the extension 33 constitutes a tenon which is engageable in the mortise or recess 32. A flexible or rubber strap 35 is adhesively secured to the cover sections 10 as shown in Figures 1 and 3 and overlaps the adjacent or inner edges of the cover sections 10a and 10b.

The strap 35 is extended downwardly against the rounded edges 14 of the cover member 10 and has portions 36 thereof adhesively secured to the upper faces of the flanges 15 and 16. The portions 36 of the strap 35 are arranged transversely of said flanges and oppositely disposed. The strap 35 at the outer ends of the portions 36, is bent downwardly at right angles, as at 37, against the front and rear edges of the supporting member 18, and such parts 37 are adhesively secured to the said edges of member 18. The strap 35 is bent inwardly from the lower ends of the parts 37 against the underside of the member 18, as at 38. The portions 38 of the strap 35 are arranged against the underside of member 18 and are the end terminal portions of said strap. The portions 38 are oppositely disposed and adhesively secured to the underside of said member 18.

One of the portions 36 of the strap 35 is arranged between the inner ends of the securing members 26 and the other portion 36 is arranged between the inner ends of the securing members 26a.

In Figure 6, there is disclosed a slightly modified form of securing means for the cushion structure and which consists of an angle-shaped holding member 39 and engages the marginal portions of the cover member 10. The angle member 39 has an upper horizontal side 40 which is adhesively secured to the forward flange 15 and the angle member 39 also has a vertical side 75

41 which is adhesively secured to the forward edge of the supporting member 18. It will be understood that the angle member 39 may also be used at the opposite ends of the supporting member 18.

5 In Figure 7, there is disclosed a further modification of this cushion structure, wherein the cover member 10c is formed with a relatively wide rear flange 42. In other respects the structure 10 shown in Figure 7 is similar in every detail to the structure shown in Figures 1 to 5, inclusive.

15 In Figure 8, there is shown a further form of coupling or connection between the adjacent ends of the fillers wherein the fillers 19c and 19d are cut off at an angle of about 45 degrees, and in Figure 9, there is shown a further form of coupling wherein the filler 19e is formed with a mortise 43 and the filler 19f is formed with a tenon 44.

20 In the use and application of the cushion structure hereinbefore described, the resilient cover member of sheet-like form is molded with the pocket 12 opening through the lower side of the sheet and the pocket 12 is disposed inwardly from the longitudinal edges and also the end edges of the sheet. The cushion body 19, which is formed of sponge rubber or the like, is initially molded to the configuration of the pocket 12 and is then inserted into the pocket 12 and vulcanized or otherwise adhesively secured therein. The width of the longitudinal flanges 15 and 16 will depend in part upon the width of the supporting member 18. Where individual cushions are desired, the resilient cover member may be formed with a plurality of spaced apart pockets 12 therein which are provided with the semi-circular end portions 13 and the pocket members 12 spaced apart at their ends for the desired distance. The cushion structure including the covering 10 and the cushion body 19 and the members 21, 26, 26a, is adhesively secured to the upper and lower sides of the supporting member 18 and at the forward and rear edges and the opposite ends of the supporting member 18. The members 21, 26 and 26a are employed so that no moisture will be able to enter the joint between the cushion structure and the supporting member 18. Furthermore, the members 21, 26 and 26a will present rounded or smooth corners which will not inconvenience the 45 limbs of a person using the cushion structure.

50 The entire cushion structure including the cover member 10, the cushion body 19 and the securing members 21, 26 and 26a are adapted to be formed out of rubber and preferably the securing members are formed out of rubber having a degree of rigidity or a density which is greater than the resiliency or density of the cover member 10.

55 What I claim is:

60 1. A cushion comprising a resilient sponge rubber body formed with rounded longitudinal and end edges, a rubber covering vulcanized to the top and longitudinal and end edges, said covering including horizontal longitudinal and end flanges extending coplanar with the bottom side of said body, and angle-shaped resilient fastening strips adhesively secured to said flanges and adapted to be adhesively secured to a support.

65 2. A cushion comprising a pair of thin resilient sheet-like members disposed in edge abutting relation, an upwardly offset pocket forming part 70 formed with each member with the pocket of one member communicating with the pocket of the other member, a cushion body in one pocket and projecting beyond one end thereof and engage-

able in the pocket of the adjacent member, a second cushion body in the pocket of said adjacent member abutting against the extended end of said first body, and a resilient strap adhesively secured to and overlapping the abutting edges of said members.

3. A cushion for elongated kneeling benches and the like comprising a resilient cover member of sheet-like form for mounting on the bench and being formed with an upwardly disposed pocket spaced inwardly from the edges of said member to provide the latter with front, rear and end flanges, means for securing said flanges to the upper face of the bench, said pocket being closed on its upper side and open on its lower side, a resilient body secured in said pocket and having its lower face flush with the lower face of said member, a pair of opposed end securing elements for the ends of the cover member engaging about the end edges and the end portions of the under side of the bench and overlapping the marginal portions of said end flanges, securing means for the front of the cover member engaging about the front edge and the front of the underside of the bench and overlapping the marginal portion of said front flange, securing means for the rear cover member engageable about the rear edge and the rear of the underside of the bench and the marginal portion of said rear flange, and a resilient strap adhesively secured to and overlying the central portion of said cover member.

4. A cushion for kneeling benches and the like comprising a resilient cover member of sheet-like form for mounting on the bench and being formed with an upwardly disposed pocket spaced inwardly from the edges of said member to provide the latter with front, rear and end flanges, means for securing said flanges to the upper face of the bench, said pocket being closed on its upper side and open on its lower side, a resilient body secured in said pocket and having its lower face flush with the lower face of said member, a pair of opposed end securing elements for the ends of the cover member engaging about the

end edges and the end portions of the under side of the bench and overlapping the marginal portions of said end flanges, securing means for the front of the cover member engaging about the front edge and the front of the underside of the bench and overlapping the marginal portion of said front flange, securing means for the rear cover member engageable about the rear edge and the rear of the underside of the bench and the marginal portion of said rear flange, and means for securing said elements and front and rear securing means to the bench and to the cover member, said front and rear securing means being interposed between and abutting said securing elements, said front and rear securing means being formed of a pair of inner endwise aligned spaced parts, and a strap disposed transversely of the outer face of said cover member, secured to the latter, disposed between the parts of the front and rear securing means, and secured to the underside of the bench.

5. A cushion for elongated kneeling benches and the like comprising a resilient cover member of sheet-like form for mounting on the bench and being formed with an upwardly disposed pocket spaced inwardly from the edges of said member to provide the latter with front, rear and end flanges, means for securing said flanges to the upper face of the bench, said pocket being closed on its upper side and open on its lower side, a resilient body secured in said pocket and having its lower face flush with the lower face of said member, a pair of oppositely disposed inwardly opening end holding elements of pocket-like form overlapping the end flanges of said cover member and the ends of the bench, a front holding means of inwardly opening channel-like form overlapping the front flange of the cover member and the front of the bench, a rear holding means of inwardly opening channel-like form overlapping the rear flange of the cover member and the rear of the bench, and a resilient strap adhesively secured to and overlying the central portion of said cover member.
